UNITED STATES PATENT OFFICE.

JEREMIAH A. SCRIVEN, OF NEW YORK, N. Y.

DESIGN FOR A BIFURCATED NETHER GARMENT.

SPECIFICATION forming part of Design No. 31,542, dated September 19, 1899.

Application filed July 17, 1899. Serial No. 724,195. Term of patent 14 years.

To all whom it may concern:

Be it known that I, JEREMIAH A. SCRIVEN, a citizen of the United States, residing in the city, county, and State of New York, have 5 invented and produced a new and original Design for Bifurcated Nether Garments, of which the following is a specification.

The leading feature of my invention is a bifurcated nether garment substantially as 10 shown in the accompanying drawing, the essential feature being the shape of the panel or insert thereof.

In the drawing the figure illustrates a rear view of a bifurcated nether garment embodying my design.

In the drawing, A designates the body por-

tion of a bifurcated nether garment having tubular members or extensions *a*, and *B* designates an insert or panel in the back of the garment. This insert or panel has inner upright edges *b* along the tubular members and has outer substantially straight edges *c*, which join curved edges *d*. The curved edges *d* extend inwardly and then outwardly from the tubular members to the band *e* of the garment. 20 25

What I claim is—

The design for a bifurcated nether garment, substantially as herein shown and described.

JEREMIAH A. SCRIVEN.
